UNITED STATES PATENT OFFICE.

SEYMOUR W. PEREGRINE, OF GRAND RAPIDS, MICHIGAN.

SCHOOL SEAT AND DESK.

SPECIFICATION forming part of Letters Patent No. 436,258, dated September 9, 1890.

Application filed February 2, 1888. Serial No. 262,716. (No model.)

To all whom it may concern:

Be it known that I, SEYMOUR W. PEREGRINE, a citizen of the United States, residing at Grand Rapids, in the county of Kent and State of Michigan, have invented certain new and useful Improvements in School Seats and Desks, of which the following is a specification, reference being had therein to the accompanying drawings.

10 The invention consists in the manner of constructing the parts and securing them together.

In the drawings, Figure 1 is a vertical section of the school-seat. Fig. 2 is a side view 15 of the inside of one of the standards. Fig. 3 is a plan view partly broken away. Fig. 4 is a section on line $x-x$ of Fig. 1.

In the drawings, A A are the standards, B the seat, and D the back. The top E of the 20 desk is provided with dovetailed grooves E' on its under side, by which it is positioned, and held by the upper edges of the standards, which are correspondingly formed. The standards are also formed with grooves e on 25 their inner sides, and into these the bottom G is inserted or slid, its position being determined by a flange f on the front edge of the standard, against which the edge of the bottom abuts. On the inside of the standards 30 are lugs g, projecting downwardly, and the sides F are also positioned by being inserted from the rear, their upper edges engaging the lugs and their lower edges being confined by shoulder h on the bottom board. The flange 35 f acts also to hold the sides in proper position. All of these parts—viz., the top, bottom, and sides—properly positioned are retained against rearward displacement by means of the back D, which abuts against the edges 40 thereof.

The front H is pivotally held by journal-pins i thereon projecting into sockets k on the standards. These sockets open downwardly, and the front is held against displacement by the top E, which covers the 45 sockets and confines the journal-pins.

In taking the desk apart the back is first removed. Then the cover is slid rearward from off the standards, and the front may then be lifted out and the sides and bottom removed. 50

What I claim is—

1. The combination, with the standards A, formed upon their adjacent faces with grooves e, lugs g, and flanges f, of the bottom G, 55 removably held in the groove, and sides F, removably held between the lugs and the side of the standard, substantially as described.

2. In a school-seat, the combination, with the standards A, having upwardly-opening bearing-sockets k formed thereon, of the 60 hinged desk-front H, having journal-pins i, and the removable top E, fitting over the bearing-sockets to retain the journal-pins, substantially as described.

3. In combination, the standards having 65 the dovetailed upper edges, the grooves e, and the lugs f, the top E, having grooves fitted to the dovetails, the bottom fitted in the grooves e, the sides fitted between the sides of the standards, and the lugs and the back fitted 70 against the edges of the top, bottom, and sides, and holding all of said parts in place, substantially as described.

In testimony whereof I affix my signature, in presence of two witnesses, this 11th day of 75 January, 1888.

SEYMOUR W. PEREGRINE.

Witnesses:

CHARLES A. RENWICK,
B. C. GIRDLER.
